UNITED STATES PATENT OFFICE

140,455

DESIGN FOR AN ICE CRUSHER

Henry J. Talge, Kansas City, Mo., assignor to John C. Hockery, Foster L. Talge, and Henry J. Talge, doing business as Rival Manufacturing Company, Kansas City, Mo.

Application November 18, 1944, Serial No. 116,437

Term of patent 14 years

(Cl. D89—1)

To all whom it may concern:

Be it known that I, Henry J. Talge, a citizen of the United States, residing at Kansas City, Jackson County, State of Missouri, have invented a new, original, and ornamental Design for an Ice Crusher, of which the following is a specification, reference being had to the accompanying drawing, forming part thereof, in which

Fig. 1 is a side elevational view of an ice crusher embodying the design,

Fig. 2 is a front elevational view of the ice crusher,

Fig. 3 is a top plan view of the ice crusher.

I claim:

The ornamental design for an ice crusher, substantially as shown.

HENRY J. TALGE.
